UNITED STATES PATENT OFFICE.

EDMUND H. BARRETT, OF BUTTE, MONTANA

TIE-PLATE.

, 1,171,581.

Specification of Letters Patent.

Patented Feb. 15, 1916.

Application filed May 27, 1914. Serial No. 841,233.

To all whom it may concern:

Be it known that I, EDMUND H. BARRETT, a citizen of the United States, residing at Butte, in the county of Silverbow and State 5 of Montana, have invented certain new and useful Improvements in Tie-Plates, of which the following is a specification.

My invention relates to tie-plates and its purpose is to provide a tie-plate, or rail 10 chair, which will also act efficiently as a rail anchor, or anti-creeping device.

In the construction and maintenance of railways it is desirable to place metal plates on the ties beneath the rails in order to provide a seat, or a chair, for the rails which will act in general to protect the ties and to prevent lateral turning of the rails about their longitudinal axes with the consequent cutting of the bases thereof into the ties. 15 Furthermore, it is common practice to employ anti-creeping devices in order to prevent the longitudinal creeping or drifting of the rails on the ties under the influence of the rolling stock. These anti-creepers 20 besides being bulky and cumbersome are often complicated and inefficient and are embodied in structures separate and distinct from the usual tie-plates, thus greatly increasing the cost of track equipment and 25 maintenance. I have therefore provided a combination tie-plate and anti-creep, which is simple, rugged, and economical in construction, durable in use, and efficient in 30 operation.

My invention simplifies the construction and avoids duplication of elements for different purposes without sacrifice of function or efficiency.

A tie-plate constructed in accordance with 40 my invention also operates to prevent the shearing of spikes owing to the lateral thrusts of the rail base, and a further feature of my invention is that it embodies improved means for preventing the displacement 45 of the plate relative to the tie.

Other objects and advantages of my invention will be set forth in the following specification, taken in connection with the accompanying drawings, in which I have 50 shown my invention as embodied in a convenient and practical form.

In the drawings—Figure 1 shows a perspective view of my improved tie-plate in operative position with respect to the base 55 of a rail; and Fig. 2 shows a bottom plan view of my improved tie-plate.

Like numerals refer to like parts and elements in the several figures of the drawings.

Referring to Fig. 1, my improved tie-plate, designated generally by the numeral 60 10, is shown in operative position with respect to the base of a rail 11. The plate 10 has formed thereon an upwardly and inwardly turned hooked jaw, or shoulder 12, which is adapted to contact with a portion 65 of the upper surface of one side of the rail base when the rail is in operative position with respect thereto. The distance between the lower surface of said jaw and the upper surface of the plate should preferably 70 be such that said jaw will firmly grip the rail base before the lateral edge of said base comes in contact with the lateral surface of the aperture, or groove, beneath said jaw. Spiking apertures 13 are provided in the 75 plate on the side thereof adjacent the jaw 12 and preferably spaced outwardly from the inner edge of said jaw, such that spikes driven therethrough will not engage the adjacent edge of the rail base in such a manner 80 as to prevent the gripping of said rail base by the jaw 12 when the rail is forced toward said jaw. The plate 10 is provided on the side thereof opposite the jaw 12 with other spiking apertures 14, which are so spaced 85 from the jaw 12 and spiking apertures 13 that when the under surface of the jaw 12 is in contact with the adjacent edge of the rail base the inner boundaries 14^a of said apertures 14 will lie inwardly of the lateral edge 90 11^a of the rail base, as clearly shown in the drawings. The spiking apertures 14 are further provided of such size that the usual spikes 15 driven therethrough will tightly wedge between the outer surfaces 14^b of 95 said apertures and the adjacent lateral edge 11^a of the rail base, thereby causing the rail base to be tightly gripped between said spikes and the opposite hooked jaw 12, thus 100 efficiently holding the rail against longitudinal creeping thereof under the influence of the rolling stock.

It will be understood that the gripping of the rail to prevent creeping thereof may also be accomplished by locating the spiking apertures 13 inwardly of the plate to such a degree that the usual spikes driven therethrough will wedge between the adjacent edge of the rail base and the outer surfaces of said apertures, thus causing the rail base 110 to be firmly held by the wedging spikes at opposite sides thereof. It is preferable,

however, to so construct the plate as to permit one edge of the rail base to tightly wedge between the jaw 12 and the adjacent surface of the plate under the influence of the 5 opposite wedging spikes 15, since a very large resistance to the creeping of the rail is thereby presented. For this purpose it is desirable to provide a relatively large area of contact between the jaw 12 and the upper 10 surface of the rail base, in order to increase the frictional resistance to movement of the rail.

The under side of the plate 10 is provided with series of relatively transverse ribs 16, 15 preferably of a knife edge form and arranged at an inclination to the principal axes of said plate. These ribs 16 are adapted to enter the fibers of the tie and prevent displacement of the plate relative thereto. 20 If desired additional ribs 17 may be provided along the lateral edges of said plate. The ribs 16 are preferably arranged at an angle to the axis of said plate, as shown, in order that they will readily enter the fibers 25 of the tie when the plate tends to move laterally, and in order that the fibers of the tie will be wedged between said ribs when a pressure is exerted on the plate after said ribs have become embedded in the tie. 30 It will be apparent that I have provided an improved tie-plate which acts as a chair, or support, for the rail and also operates efficiently to prevent longitudinal creeping of the rails relative to the ties. It will further be evident that when my tie-plate is 35 used with the jaw 12 toward the outer side of the railway track, said jaw, or shoulder,

will operate to prevent the shearing of the spikes, which pass through the apertures 13, owing to the lateral thrust of the rail. 40

While I have shown and described a particular form which my invention may take, it will be understood that it may be embodied in other structures of widely divergent form, and I therefore do not wish to be 45 limited in the scope of my invention except as defined by the appended claim.

I claim:

In a device of the class described, a plate adapted to rest upon a tie and support a 50 rail, said plate having an upwardly and inwardly directed jaw adapted to engage the upper surface of a rail base, said jaw being formed to leave a clearance between the lateral edge of said rail base and the junction 55 of the lower surface of said jaw with the upper surface of said plate, said plate having a spiking aperture adapted to be overlapped by the edge of the rail base opposite said jaw when said rail base is in contact 60 with said jaw, the uncovered portion of said aperture being of less width transversely of the rail than the usual spike adapted to be used therewith whereby the driving of said spike forces the rail base into wedging 65 engagement between said jaw and the upper surface of said plate.

In testimony whereof, I have subscribed my name.

EDMUND H. BARRETT.
